REFINING OF MINERAL OILS

Shanti Swarupa Bhatnagar, Lahore, India, assignor to Steel Brothers & Company Limited, London, England

Application June 15, 1936, Serial No. 85,409
In Great Britain August 19, 1935

9 Claims. (Cl. 196—13)

Crude petroleum is separated by distillation into various fractions such as petrol, kerosene, gas oil, Diesel fuel oils, lubricating oils, etc., some of which require a refining treatment in order to render them suitable for use.

In the case, for instance, of the kerosene fraction, which usually distils between the approximate limits of 150° C. and 300° C., such a treatment is generally required for improving the 10 burning qualities of the oil with respect to luminosity, tendency to smoke and incrustation of the wick, and for reducing the tendency to discoloration during storage. The known treatment with strong or fuming sulphuric acid or with adsorbents is not satisfactory in the case of kerosenes of inferior quality, containing a relatively high percentage of undesirable constituents, for example, aromatic and unsaturated hydrocarbons, etc., and such kerosenes are usually refined 15 by treatment with certain selective solvents which extract the undesirable constituents of the oil; such solvents are, for instance, liquid sulphur dioxide, phenol, alcohol and acetone, of which only the first-named has found extensive commercial application.

The lubricating oil fraction (which may be a distillate or may constitute the distillation residue according to its grade and to the nature of the crude petroleum) is in some cases treated 20 with a selective solvent in order to improve its viscosity index and resistance to oxidation and to reduce its tendency towards the formation of gum and/or carbon deposits when used in internal combustion engines. As such solvents, furfural, nitrobenzene, a mixture of benzene and sulphur dioxide, and cresylic acid in conjunction with liquid propane, have been proposed among others.

The use of selective solvents has also found 25 application in the improvement of Diesel fuel oils, especially in the case of oils for use in the so-called high speed Diesel type of engine, in which the presence of as large a proportion as possible of paraffinic constituents is desirable for satisfactory ignition qualities. Such solvents are used for extracting the inferior constituents having poor ignition qualities, leaving a more highly 30 paraffinic refined oil.

According to this invention, mineral oils are 35 refined by subjecting them to extraction with glacial acetic acid. It has been found that this acid has a good selective solvent action on the undesirable constituents of the oils; furthermore, it is easily recovered unchanged and its use does 40 not necessitate operation under pressure or at

low temperatures. In the case of some oils it 5 may be advantageous to dilute the oil under treatment with lighter hydrocarbons to reduce its viscosity and permit a more efficient separation of the undesirable constituents, and subsequently recover the diluent by distillation, or alternatively to carry out the process under temperatures or pressures other than atmospheric.

The invention is useful in its application to any petroleum fractions, in particular, burning 10 oils, lubricating oils and Diesel fuel oils.

From a low grade kerosene it is possible to obtain a refined product of excellent burning qualities and in good yield. It has been found that from certain kerosenes of only average burning 15 qualities, it is possible to obtain yields of much improved oils as high as 92 per cent. of the original oil; if only a smaller degree of improvement is desired, even higher yields may be obtained.

Crude lubricating oils are substantially improved in their viscosity index, their resistance 20 to oxidation and their colour stability and may only require a final treatment with an adsorbent earth in order to give products of high quality and good colour.

From low grade Diesel fuel fractions it is 25 possible to produce refined oils of much improved paraffinicity and correspondingly improved ignition qualities.

In carrying out the invention, the procedure 30 may consist in intimately mixing the oil with a suitable quantity of glacial acetic acid and then allowing the mixture to separate into layers. The quantity of glacial acetic acid may vary from, say, one half to three times the volume of 35 the oil depending on the nature of the oil and the degree of refining desired, although a larger quantity may be used. The upper layer (raffinate layer) constitutes the refined oil containing some acetic acid, generally about 15 per cent. at atmospheric temperatures of 26-27° C. and a smaller quantity at lower temperatures. The lower layer constitutes the extract and consists of the balance of the acetic acid containing the undesirable portions extracted from the original oil.

It is possible to conduct the process more 40 economically by subjecting the oil to several successive extractions. In this case, the total quantity of glacial acetic acid is divided into several 45 portions which are used successively for the extraction of a given quantity of oil; that is to say, the oil is first mixed with one portion of the acid and allowed to separate, the extract is removed 50 and the partially refined oil is then treated in like manner with a further portion of the acid, 55

and so on. In this manner, the proportion of acetic acid required for producing a desired result may be reduced and the yield of refined oil of a given quality increased. The most suitable number of stages depends in any given case on the total proportion of acetic acid to be used and on the available plant; generally a treatment with a volume of acetic acid varying from 100 to 250 per cent. of the volume of the oil can be advantageously conducted in three or four stages.

The process may be conducted according to the counter-current system. The operation may be continuous, the glacial acetic acid and the oil to be treated passing in opposite directions through any suitable counter-current plant so that the fresh acetic acid first comes into contact with an oil from which the bulk of the undesirable constituents has already been removed, whilst the fresh oil first comes into contact with acetic acid which has a relatively high content of undesirable constituents extracted from a previous quantity of oil. Alternatively, the counter-current system may be applied in the extraction of the oil in batches; in this case, each batch of oil will be subjected to extraction in several successive stages, there being used for the final stage fresh glacial acetic acid and for each of the other stages the oil-containing acid constituting the extract from the next succeeding stage of the extraction of a previous batch of oil.

The glacial acetic acid and the oil may be mixed by means of a stirrer, a pump and orifice mixer, a homogenizer or an orifice mixer fed by gravity. The raffinate and extract may be allowed to separate in a settling vessel or they may be separated in a centrifugal separator.

Various methods are available for recovering the acetic acid contained in the extract and in the raffinate, such as washing with water, distillation, steam distillation, salting out or cooling to a sufficiently low temperature to cause crystallization of the acid. Which method or combination of methods is most advantageous for treating the raffinate and the extract respectively will depend on the circumstances of each particular case.

For example, the refined oil may be substantially freed from acetic acid by washing with water, most advantageously applied in successive portions. The washing water containing the extracted acetic acid may then be used for washing an extract which has already been freed from the bulk of its acetic acid by washing or otherwise.

According to another procedure, the acid may be recovered from the raffinate or extract, or from both, by distillation, with or without the assistance of reduced pressure. In the case of kerosene, however, distillation tends to cause a slight discoloration of the refined oil, so that a subsequent treatment with, for instance, sulphuric acid or an adsorbent earth may be necessary to restore the colour. Distillation may be conducted in any suitable type of plant, such as a tube still having a flash tower in which the acetic acid vapour is released, or a climbing film or similar type of evaporator in which the vapour is released by centrifugal force. Heat may be economized by heat exchange between the vapour or hot oil leaving the plant and the incoming mixture of oil and acetic acid. Whilst distillation may be conducted under reduced pressure, it is generally more convenient to operate under atmospheric pressure owing to the tendency to dilution of the acid if a steam ejector

is used for providing the reduced pressure, and to the danger of corrosion of working parts if a vacuum pump is used. Any oil carried over with the acetic acid vapour during distillation is of good quality, even in the case of the extract, and its presence does not interfere with the re-use of the recovered acid in the process.

Yet another procedure for recovering acetic acid consists in "salting out" the bulk of the acid by means of anhydrous sodium acetate; the acid still remaining in the oil may then be substantially removed by washing with water. The acetic acid salted out may be separated from the sodium acetate by distillation.

Steam distillation will scarcely be an economical method for the recovery of acid from oils containing it in substantial proportions but may sometimes usefully be adopted for the treatment of oils from which the bulk of the acid has been removed by some other means, such as distillation.

In all cases in which the treatment of the extract or raffinate leads to an aqueous solution of acetic acid, glacial acetic acid may be recovered from the solution by azeotropic distillation and may be used again in the process. Alternatively, the aqueous acid may be used for some other purpose, for example for the manufacture of esters.

In some cases it may be desirable to subject the refined oil to distillation in order to improve its colour and to free it from the last traces of acetic acid. Or the last traces of acid may be removed by treatment with an alkali, such as sodium hydroxide or lime, followed by washing with water.

The invention permits the production of burning oils of very high quality from an unrefined oil of the approximate distillation range of 150° to 250° C.; in this case it is advisable to recover the acetic acid from the raffinate by washing with water.

Where a very high quality is not the main desideratum, it may be found preferable to use an unrefined oil of somewhat higher distillation range, say about 200° to 310° C., and to mix the refined oil obtained therefrom with a fraction of the unrefined burning oil of lower distillation range (say 150-200° C.). This procedure leads to a burning oil which is of good quality and is distinctly superior to the unrefined fraction. It has the advantage that the larger interval between the boiling point of acetic acid and the initial distillation temperature of the oil facilitates the recovery of the acid by distillation, both from the raffinate and from the extract.

The oil obtained from the extract may be used for various purposes, according to its nature and source; thus it may be useful as a fuel oil, or as a parent material for the manufacture of petroleum resins, or it may be cracked to produce petrol or oxidized to produce asphaltic substances.

When an oil has been treated with a relatively large proportion of acetic acid, it is possible to recover from the extract, by controlled addition of water, an oil which is superior to the untreated oil. This oil may if desired be combined with the refined oil resulting from the treatment. Controlled dilution of the extract with successive quantities of water may be utilized for separating fractionally oils of progressively decreasing quality. Similar results can be obtained by the controlled addition of an anhydrous acetate,

such as sodium acetate, instead of water, to the extract.

It has been found that the presence of even small quantities of water in the acetic acid detracts appreciably from its value as an extracting agent. Generally, it may be said that the glacial acetic acid should be of at least the commercial concentration of 98.9 per cent. strength, although an appreciable degree of refining can still be obtained with an acid containing about 97 per cent. of acetic acid, especially when the unrefined oil is a kerosene of relatively good quality.

When, as will frequently be the case, the unrefined oil contains small quantities of water in solution or suspension, repeated use of the acid will involve progressive dilution and loss of efficiency unless steps are taken to counteract this. For this purpose, the acid may be treated periodically to restore its concentration or a portion of the acid may be withdrawn continuously and returned to the process after its concentration has been restored.

It has been found, however, that moderately dilute acetic acid, containing about 85 per cent. of acetic acid, is still capable of extracting from the unrefined oil a part of the undesirable constituents which may be used for other purposes. Hence it may be advantageous to subject unrefined oils containing water in solution or suspension to a preliminary extraction with a diluted acetic acid of about 85 per cent. strength, thereby removing simultaneously the bulk of the water and a fraction of the undesirable constituents useful as a fuel oil, the remainder of the undesirable constituents being then removed by extraction with glacial acetic acid.

A suitable manner of carrying out the invention will now be described by reference to the accompanying drawings, in which:—

Fig. 1 shows diagrammatically a four-stage counter-current plant for the extraction and

Fig. 2 is a flow sheet illustrating the recovery of the acetic acid from the raffinate and the extract by washing with water.

Referring to Fig. 1, M₁, M₂, M₃ and M₄ are mixing tanks communicating through pumps P₁, P₂, P₃ and P₄ and orifice mixers O₁, O₂, O₃ and O₄ by way of pipes C₁, C₂, C₃ and C₄ with centrifugal separators CS₁, CS₂, CS₃ and CS₄ whose outlets are connected respectively by pipes F₁, F₂, F₃ and F₄ with a pipe line A and by pipes G₁, G₂, G₃ and G₄ with a pipe line B. The pipe lines A and B have branch pipes D₁, D₂, D₃ and D₄ and E₁, E₂, E₃ and E₄ respectively which discharge into the mixing tanks M₁, M₂, M₃ and M₄. The pipe lines A and B and the branch pipes D₁, D₂, D₃, D₄ and E₁, E₂, E₃, E₄, are provided with valves H and K, which are arranged so that any of the mixing tanks and its associated separator can be disconnected from the system.

Unrefined oil enters the plant at the right-hand end of the line A and glacial acetic acid at the left-hand end of the line B. The valves H being closed and the valves K being open, the unrefined oil enters the tank M₄ by way of the branch pipe D₄ and glacial acetic acid enters the tank M₁ by way of the branch pipe E₁. The flow of acid and oil through the apparatus is continuous and is regulated by level controls LC₁, LC₂, LC₃ and LC₄. In the tank M₁ the fresh acetic acid meets partially refined oil delivered from the separator CS₂ by way of pipe F₂, pipe line A and branch pipe D₁. The mixture is forwarded by the pump P₁ to the separator CS₁, which delivers the refined oil to the

pipe line A and thence to the outlet from the plant. The acetic acid extract is delivered by way of pipe G₁, pipe line B and branch pipe E₂ to the tank M₂, where it meets partially refined oil from the separator CS₃, and so on. The liquids in each of the tanks M₁, M₂, M₃, M₄ are mixed by means of the pumps P₁, P₂, P₃, P₄, and orifice mixers O₁, O₂, O₃, O₄; discharge of the mixture from the mixers is controlled by pressure regulators PR₁, PR₂, PR₃, PR₄, so arranged that a portion of the mixture is returned continuously to the tanks M₁, M₂, M₃, M₄, and the pumps P₁, P₂, P₃, P₄, thus increasing the time of contact of the acid and oil.

Referring to Fig. 2, from the extraction section 1 (which may be a plant of the kind shown in Fig. 1) refined oil containing, for instance, about 15 per cent of acetic acid passes to the refined oil washing section 2, where it is washed with water containing a trace of acetic acid from the final extract washing section 3. The extract from section 1 passes to the extract release section 5, in which the bulk of the extracted oil is released from solution by treatment with water from the extract washing section 4, and the released oil then passes into the extract washing section 4 in which it is washed with water which has already been used for washing the refined oil in section 2 and contains some acetic acid. The washed extract from section 4 is then freed from the small quantity of acetic acid still remaining in it by washing with fresh water in the final extract washing section 3, the wash water thence passing to the refined oil washing section 2. The refined oil leaving section 2 and the extracted oil leaving section 3 may finally be freed from any residual trace of acid by washing with alkali. The aqueous acetic acid from section 5 passes to the recovery section 6 in which the acid is recovered by azeotropic distillation and a small quantity of extracted oil contained in it is separated. In each washing section, the washing may be conducted according to the counter-current system or with successive portions of the washing liquid.

The procedure illustrated in Fig. 2 provides an economical method of recovering acetic acid with use of a minimum quantity of water.

The following are examples of the application of the invention, the parts being by volume:—

Example 1.—100 parts of a kerosene oil of approximate boiling range 205°–290° C. and a smoke point 14.5 mm. (as determined by the smoke point method of the Institution of Petroleum Technologists) were treated with 200 parts of glacial acetic acid in counter-current in four stages. The raffinate layer contained about 15 per cent. of acetic acid, from which it was nearly completely freed by washing with water in stages, leaving 68.5 parts of an oil having a smoke point 23 mm. Addition of the aqueous washings to the extract caused the separation of a yellow oil having an acetic acid content of about 4.77 per cent.

A second batch of 100 parts of kerosene was treated in like manner, but the washings from the raffinate, instead of being used directly for releasing oil from the extract, were first used for washing the yellow oil previously released from the first extract, whereby its content of acid was reduced to less than 0.2 per cent. The washing water containing acetic acid was then used to release dissolved oil from the second extract. The washed oil originating from the first extract was then washed substantially free from acetic acid by means of a small quantity of fresh water which was then used for washing the raffinate from a third batch of oil. The process can now

be continued in as many stages as desired as illustrated in Fig. 2.

Example 2.—100 parts of a kerosene oil of the approximate boiling range 205°–310° C. and smoke point 15.5 mm. were treated with 250 parts of glacial acetic acid in four stages and the raffinate and extract were freed from the bulk of the acid contained in them by distillation at atmospheric pressure. The raffinate layer contained about 0.5 per cent. of acetic acid and yielded after washing with water and alkali 68 parts of an oil having a smoke point 24.5 mm. The extract yielded an oil residue having an acetic acid content of about 0.8–0.9 per cent. The combined acetic acid distillates contained about 3 per cent. of oil.

When the distillations were conducted under reduced pressure (5–6 mm.), there was obtained a refined oil containing about 0.03 per cent. of acetic acid and an extract oil containing somewhat less than 0.07 per cent. of acetic acid. The acetic acid distillates contained 1.6 per cent. of oil of very pale colour.

Example 3.—100 parts of kerosene having a smoke point 18 mm. yielded on treatment in one stage with 300 parts of glacial acetic acid 45 parts of refined oil having a smoke point 29 mm. and an acetic acid extract from which by addition of sodium acetate there were recovered 47 parts of oil having a smoke point 19 mm., representing a total yield of 92 per cent. of oil of smoke point 24 mm.

Example 4.—100 parts of a normal kerosene fraction of approximate boiling range 180°–290° C. and a smoke point 18 mm. yielded on treatment with a total quantity of 137 parts of glacial acetic acid applied in three successive stages, 73.2 parts of a raffinate having a smoke point 25.5 mm. The acetic acid was distilled from the extract and the distillate yielded on dilution with water, 9.3 parts of an oil of smoke point 19.5 mm., representing a total yield of 82.5 parts of an oil of smoke point 24.8 mm. The oil remaining as the distillation residue amounted to 16.3 parts and had a smoke point 9 mm.

Example 5.—100 parts of a petroleum fraction suitable as a base for making lubricating oil were treated with 250 parts of glacial acetic acid and the raffinate, after separation from the extract, was treated with further 250 parts of glacial acetic acid. The raffinate from this second treatment was washed with water until free from acid and yielded 82 parts of an oil having the characteristics shown in the following table, those of the untreated oil being given for comparison:—

	Treated oil	Untreated oil
60 Redwood No. 1 viscosity at:		
40° C.....	507 secs.....	690 secs.....
60° C.....	170.8 secs.....	205 secs.....
100° C.....	54 secs.....	55.3 secs.....
Sp. gr. at 15° C./15° C.	0.939.....	0.955.....
65 Colour (transmitted light).....	Red.....	Opaque.....
Colour (reflected light).....	Red-green bloom.....	Blue-black.....

It will be seen that the treatment has resulted in an improvement in the viscosity temperature coefficient and in the colour and in a reduction of the specific gravity.

The extract was a sticky black oil of specific gravity exceeding unity at 15° C./15° C.

Example 6.—100 parts of unrefined kerosene of approximate boiling range 205°–290° C. and smoke point 14.5 mm. were treated in one stage

with 200 parts of glacial acetic acid. After separation of the raffinate, the extract was diluted with water until 10 parts of oil had separated; this was removed and water was again added until further 10 parts of oil had separated. After removal of this oil, the residue was diluted with an excess of water.

The oils separated at each stage of the dilution were progressively darker and of diminishing burning properties. The fraction first separated was superior to the original unrefined oil having a smoke point 16.5 mm. and being nearly colourless. The second fraction had a smoke point 8.5–9 mm. and was darker in colour, whilst the final fraction, amounting to 4.5 parts had a smoke point 5 mm. and was deep brown.

Example 7.—100 parts of a gas oil fraction of smoke point 14 mm. and specific gravity 0.8675 (15° C./15° C.) were treated in one stage with 300 parts of glacial acetic acid. There were obtained 72 parts of a raffinate having an improved paraffinicity, as is shown by its increased smoke point (19.5 mm.) and decreased specific gravity (0.8555). The acetic acid was distilled from the extract, leaving a residue of smoke point 7 mm.

Having thus described the nature of the said invention and the best means I know of carrying the same into practical effect, I claim:—

1. A process for refining liquid petroleum oil fractions which comprises subjecting the fraction to extraction with a quantity of acetic acid of at least 97 per cent. strength amounting to at least about half the volume of the fraction and separating from one another the layers of refined oil and extract thus formed.

2. A process for refining liquid petroleum oil fractions which comprises subjecting the fraction first to extraction with acetic acid of about 85 per cent. strength, separating from one another the layers of oil and extract thus formed, subjecting the separated oil to extraction with a quantity of acetic acid of at least 97 per cent. strength amounting to at least about half the volume of the oil and separating from one another the layers of refined oil and extract thus formed.

3. A process for refining liquid petroleum oil fractions which consists in mixing the fraction with a quantity of acetic acid of at least 97 per cent. strength amounting to at least about half the volume of the fraction, separating from one another the layers of refined oil and extract thus formed, washing the refined oil layer with water, diluting the extract layer with the water which has already been used for washing the refined oil layer and contains some acetic acid and separating the oil thus released.

4. A process for refining liquid petroleum oil fractions which consists in mixing the fraction with a quantity of acetic acid of at least 97 per cent. strength amounting to at least about half the volume of the fraction, separating from one another the layers of refined oil and extract thus formed, diluting the extract layer and separating the oil thus released, washing the separated oil with water and using the aqueous washings first for washing the refined oil layer and subsequently for diluting a further quantity of the extract layer to release extracted oil therefrom.

5. A process for refining liquid petroleum fractions which consists in mixing the fraction with a quantity of acetic acid of at least 97 per cent. strength amounting to at least about half the volume of the fraction, separating from one another the layers of refined oil and extract thus formed, mixing the extract layer in stages with

- successive quantities of water and separating the oil released in each stage.
5. 6. A process for producing a burning oil, which comprises subjecting a kerosene oil fraction of petroleum to extraction with a quantity of glacial acetic acid amounting to at least about half the volume of the fraction, and separating from one another the layers of refined oil and extract thus formed.
10. 7. A process for obtaining a lubricating oil, which comprises subjecting a lubricating oil fraction of petroleum to extraction with a quantity of glacial acetic acid amounting to at least about half the volume of the fraction, and separating from one another the layers of refined oil and extract thus formed.

8. A process for obtaining a Diesel fuel oil, which comprises subjecting a Diesel fuel oil fraction of petroleum to extraction with a quantity of glacial acetic acid amounting to at least about half the volume of the fraction, and separating from one another the layers of refined oil and extract thus formed.

9. A process for obtaining a burning oil, which comprises subjecting the higher boiling portion of a kerosene oil fraction of petroleum to extraction with a quantity of glacial acetic acid amounting to at least about half the volume of the said portion and mixing the raffinate thus obtained with the lower boiling portion of the kerosene oil fraction.
